CLAIM

The ornamental design for a gas detection device as shown and described.

DESCRIPTION

FIG. 1 is a front perspective view of a gas detection device for a gas detection device;

FIG. 2 is a rear perspective view of the gas detection device thereof;

FIG. 3 is a front view of the gas detection device thereof;

FIG. 4 is a rear view of the gas detection device thereof;

FIG. 5 is a left side view of the gas detection device thereof;

FIG. 6 is a right side view of the gas detection device thereof;

FIG. 7 is a top view of the gas detection device thereof; and,

FIG. 8 is a bottom view of the gas detection device thereof.
